UNITED STATES PATENT OFFICE.

GEORGE F. PARKER, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A PLATE OR ANALOGOUS ARTICLE.

Application filed March 19, 1929. Serial No. 30,521. Term of patent 14 years.

To all whom it may concern:

Be it known that I, GEORGE F. PARKER, a citizen of the United States, residing at Newburyport, in the county of Essex and Commonwealth of Massachusetts, have invented a new, original, and ornamental Design for a Plate or Analogous Article, of which the following is a specification, reference being had to the accompanying drawing, forming a part thereof.

In the drawing, Figure 1 is a plan view and Fig. 2 is a view in elevation of a plate showing my new design.

The dominant feature of the design consists of the border ornamentation.

I claim:

The ornamental design for a plate or analogous article, substantially as shown and described.

GEORGE F. PARKER.
